UNITED STATES PATENT OFFICE

2,226,985

VALVE ACTUATING MECHANISM

Louis R. Spencer, West Hartford, Conn.

Application May 9, 1939, Serial No. 272,656

2 Claims. (Cl. 123—90)

This invention relates to improvements in valve actuating mechanisms of the type wherein a rocker arm engages the valve stem for effecting reciprocatory motion of the latter.

The rocker arm itself is generally actuated by means which rock the arm in one direction to move the valve stem in one direction, while the stem and arm are returned in the opposite direction usually by a spring. During this 10 turn motion, difficulties have been encountered in some structures in maintaining a flat contact between the surface of the rocker arm and the surface of the rocker arm actuator and the primary object of the present invention is to provide a valve actuating mechanism wherein it is insured that the surface of the rocker arm will lie flat against the surface of its actuating member at all times.

A further object of the invention is to provide a rocker arm for a valve actuating mechanism which is capable of rotating in a plane transversely of the plane in which the rocker arm is rocked.

A still further object of the invention is to provide a valve actuating mechanism wherein the rocker arm is permitted a limited longitudinal movement.

More specifically, the invention contemplates a valve actuating mechanism wherein the rocker arm is journaled in a member which is rotatable in a plane transversely of the plane in which the rocker arm rocks, said member, together with the arm, possessing a limited movement axially of said member or longitudinally of the arm, and the rotary motion of said member being limited to the desired degree.

With these and other objects in view, the invention consists in certain details of construction and combinations and arrangements of parts, all as will hereinafter be more fully described, and the novel features thereof particularly pointed out in the appended claims.

In the accompanying drawing—

Figure 1 is a sectional, elevational view, longitudinally of the rocker arm, the latter being shown in full;

Fig. 2 is a horizontal, sectional view on the line 2—2 of Fig. 1;

Fig. 3 is a vertical, sectional view on the line 3—3 of Fig. 1; and

Fig. 4 is an end elevation illustrating, in full lines, the normal engagement between the rocker arm and its actuator and, in dotted lines, the abnormal engagement of said elements that

would be possible in the absence of the present invention.

In the construction illustrated, the rocker arm 10 is adapted to be rocked by a cam 11 mounted on cam shaft 12, the downward motion of the 5 valve stem 13 caused by the depression of the rocker arm compressing springs 14 which will return or elevate the stem and rocker arm as the cam 11 continues to revolve and the lower portions of the cam surface come into engagement with said rocker arm. Usually, the upper surface of the rocker arm which engages against the surface of the cam 11 is curved longitudinally, as illustrated and, heretofore, difficulties 10 have been encountered by reason of the accuracy with which the surface of the actuator, the cam 11 in the present instance, and the surface of the rocker arm has to be assembled. In other words, it requires a high degree of accuracy in assembling the rocker arm and its actuator 15 to cause the curved surface of the rocker arm to lie or engage flat against the surface of its actuator or cam 11. In the event the rocker arm does not lie flat against the surface of the cam, particularly during the upward movement 20 of the rocker arm, the metal at the contact point will be overstressed and start breaking away. This so-called abnormal engagement of the rocker arm and cam surface can be more readily appreciated by an inspection of Fig. 4, wherein 25 the rocker arm is illustrated, in dotted lines, as being slightly tilted, under which circumstances it will be seen that it makes a point contact with the cam surface 11, as distinguished from a line contact. Naturally, where there is such a point 30 contact, stresses are localized and, consequently, the tendency of the metal to break away.

In accordance with the present invention, these difficulties are eliminated by permitting the rocker arm to rotate substantially on its longitudinal center or in a plane transversely of the plane in which it is adapted to be rocked by its actuating cam. For instance, the rocker arm may be journaled to rotate in bearings 15 formed in a circular member 16 which, likewise, is journaled for rotary motion in the wall 17 of the motor casing or block, the rotary motion permitted the circular member 16 being in a plane transversely of the rocker arm or the plane in which the rocker arm is adapted to rock in its bearings 40 45 15. In the present instance, the rocker arm is provided with trunnions 18 journaled in the bearings 15, but it will be appreciated that these trunnions are no more, in effect, than a shaft 50 55 on which the rocker arm might either be fixed

or pivotally supported. The essential point is that the member 16 shall be capable of rotating in the recess in which it is seated in the engine block, and that the plane in which said member rotates shall be disposed transversely of the plane in which the rocker arm rocks.

Only a limited rotary motion of the circular member 16 is required to permit or insure proper engagement of the rocker arm with the rocker cam. For limiting the rotary motion of said member, the surface thereof is formed with an axially disposed slot 19 and, extending through the engine block into said slot, there is a pin 20, the width of said pin transversely of said slot being slightly less than the width of the slot itself, as illustrated in Fig. 3. Thus, the rotary motion of member 16 is limited to the clearance that is provided between the pin 20 and the side walls of recess 19. With this arrangement, any slight error in the assembly of the rocker arm and its actuating cam can be easily corrected, or will be compensated for, by the member 16 automatically adjusting itself circumferentially to accommodate the surface of the rocker arm against the surface of the cam in a flatwise relationship.

The cam 11 is rotated in the direction of the arrow 21, in Fig. 1, and, as a consequence, there is a longitudinal pull imposed on the rocker arm 20 in the direction of the arrow 22, so that there is a tendency to force the member 16 against the inner surface of the recess in which it is seated, but to insure maintenance of the member 16 in this position, means are provided for imposing

an endwise thrust directly on said member. For instance, one or more springs 23 may be interposed between said member 16 and the cover plate 24 for the recess in which said member is seated. Thus, the springs constantly urge the member 16 and the rocker arm toward the cam and valve stem, the movement of said members in that direction being, of course, limited by the inner wall of the recess. In this way, the rocker arm maintains a constant relationship with respect to its actuating cam and the valve stem, notwithstanding the fact that it is carried on what might be termed a floating member. In other words, although the circular member 16 is, in a sense, free in its recess, the longitudinal disposition of the rocker arm is constant.

What I claim is:

1. In a valve actuating mechanism, a cylindrical rotatable member closed at one end, means engageable with said end yieldingly urging said member axially in the direction of its opposite end, a rocker arm pivoted in said member and projecting from said opposite end, and a stop engageable with said member for limiting the rotary motion thereof.

2. In a valve actuating mechanism, a cylindrical rotatable member, a rocker arm pivotally supported in said member and projecting from one end thereof, means for limiting rotary motion of said member, and means yieldingly urging said member axially in the direction in which the rocker arm projects from said member.

LOUIS R. SPENCER.
